ATTORNEY

UNITED STATES PATENT OFFICE.

JOSEPH M. WHITE, OF LACONIA, NEW HAMPSHIRE.

DEVICE FOR CARRYING KEYS.

Application filed April 9, 1926. Serial No. 100,940.

The object of this invention is to provide a purse or other form of flexible container including means secured thereto for carrying a plurality of keys on separate key-holding devices.

A further object is to provide a case preferably formed of flexible material, and mounting on one of the inner walls thereof a pivoted bar carrying hooks by means of which the keys are separately attached.

A further object is to mount the separate hooks by means of sleeves which are rotatable on the bar.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 is a view of the device in perspective, the side members being in closed position.

Figure 2 is a perspective view, the purse being in open position, the bar mounting the individual key-holding devices having been rotated about a central pivot, in order that the keys may be positioned for use.

Figure 3 is a view in elevation, with a portion broken away, in order to show the key mounting means in detail.

Figure 4 is a section longitudinally thru the casing.

Figure 5 is a detail in section on line 5—5 of Figure 3.

The case includes the side members 10 and 11, a fold being formed at 12, and the edges 40 being stitched together at 13.

The other edge portions are stiffened by means of rods, such as 14 inserted in the rolled portions 15 and 16 and 15', at the end of the container. The corners at the 45 lower right hand portion of Figure 2 are reinforced by metallic corner members 17, and a catch 18 is pivoted on one of said bars 14,

and is adapted to engage the other bar 14 at the point 14', for retaining the purse in closed position.

An important feature of the construction is the pivoted element at the end of the container opposite the stitched portion 13.

A middle sleeve 20 has connected therewith a pin 21 which is rotatably secured in the wall 55 11, and a bar 22 extends thru sleeve 20, and is rotatable with the sleeve about an axis defined by element 21.

Other sleeves 23 mounted on bar 22 have connected therewith hooks 24, and the sleeves 60 are rotatable with reference to bar 22, so that the keys to be applied to the hooks may be easily moved in any direction desired. It will be observed that because of the main pivotal mounting at 20, and the individual 65 loosely mounted sleeves, the device may readily be employed under any circumstances likely to arise, the keys always being inclosed when the purse is carried in the pocket, and the bar 22 being swung to the position of 70 Figure 2, when any of the keys is to be used. The closed and locked position is clearly shown in the other views of the drawing.

Having thus described the invention, what I claim is:

1. In a device of the class described, a container including side walls, some of the edges of which are connected together, the remaining edge portions each including a stiffening element, means for securing and retaining 80 the side walls in parallel relation, individual key mounting devices, a bar on which these devices are independently movable, and means for pivotally mounting the bar on one of the side walls of the container, near a free 85 edge thereof.

2. In a key case, mounting means for the keys, comprising a pivoted bar mounted for angular movement about an axis, and key retaining means mounted on the bar, and independently movable with reference thereto.

In testimony whereof I affix my signature.

JOSEPH M. WHITE.
